UNITED STATES PATENT OFFICE.

GEORGE ST. PIERRE, OF OAKLAND, CALIFORNIA.

BEARING-BOX.

SPECIFICATION forming part of Letters Patent No. 448,462, dated March 17, 1891.

Application filed June 24, 1890. Serial No. 356,563. (No model.)

To all whom it may concern.

Be it known that I, GEORGE ST. PIERRE, a citizen of the United States, residing at Oakland, in the county of Alameda and State of California, have invented new and useful Improvements in Bearing-Boxes; and I do hereby declare the following to be a full, clear, and exact description of said invention, reference being had to the accompanying drawings, and to the letters or figures of reference marked thereon, which form a part of this specification.

My invention relates to new and useful improvements in bearing-boxes and devices for feeding a lubricant to the bearings.

The object of the invention is to provide an oscillating bearing-box for the journals of constantly-rotating shafts—such as are found in the channels of cable railways carrying the sheave on which the cable runs—and also combining therewith a self-feeding oil-cup of the type known as "liquefiers," by which the bearing is automatically supplied with oil. By such provisions the wearing and heating of the bearing, looseness of play of shafts, and other objectionable consequences incident to the operation of these parts are provided against to such an extent as to form a perfectly-operating bearing at all times.

The invention consists in combined oil-cup and bearing-boxes having trunnions, and in mounting the boxes upon said trunnions in brackets provided with recesses or slots for the reception of the trunnions, by which mounting they are permitted to oscillate in the direction of the shaft's length and to accommodate themselves to the journals, thus insuring perfect bearing-surfaces within the bearing-boxes and at all times a uniform bearing, notwithstanding the play or shifting of the shaft; and certain novel features in the arrangement and construction of the boxes, by means of which the bearings can be easily removed and new ones inserted, and a discharge provided for the lubricant after it has been used, all as hereinafter explained.

In the accompanying drawings, Figure 1 is a front elevation of a cable-carrying sheave, and the shaft on which it is secured is mounted in my combined bearing-boxes and oil-cups, the left-hand bearing-box and the cable-car-

rying sheave being shown in section. Fig. 2 is a view in front elevation of the oscillating bearing-box and oil-cup, showing the trunnions for giving it an oscillating support and 55 the lignum-vitæ bearing. Fig. 3 is a front elevation of the bracket for supporting the bearing-box.

As before intimated, the objects sought to be attained by this invention are particularly 60 of great value where the wear and friction are constant, as in the bearings of cable roads, and I have illustrated the invention as applied to the journals of the shafts carrying the cable-sheave.

Referring to the illustration, A indicates the cable-carrying sheave secured to the shaft B, the journals C of said shaft finding their bearings in the bearing-boxes D, which are permitted to oscillate in the direction of the 70 shaft. These combined oil-cups and bearing-boxes E have the trunnions *a a* cast thereon, by which the combined oil-cups and bearing-boxes are supported in the brackets F, and the oil-cups G, which are preferably made integral with the bearing-boxes, are formed with 75 a central opening *b*, which communicates with the opening *d* in the bearing-boxes for the reception of the shafts. Into these central openings are inserted the copper pins *e*, which 80 are free to rest on the journal of the shaft, and which by becoming heated by the friction produced by their contact with the revolving journal melt the thick lubricant *f* around them, which feeds through to the bearings. The 85 vibration of the pins *e*, owing to the motion of the shaft, also assists materially in feeding the lubricant. The cups *G* are fitted with the covers *g*, provided with perforations *h h* to admit air to the interior in order to allow the 90 lubricant to feed down to the bearings.

The central openings *d* in each bearing-box E are formed of such shape as to receive a bearing-block of lignum-vitæ *i*, which is a rectangular block, and which, with its semi-circular groove corresponding to the remaining semicircular portion of the opening not filled by the bearing forms a circular opening or recess for the journal. Each opening or recess *d* extends nearly through the bearing-box, but allows the bearing-block of lignum-vitæ and the journal to come in contact with 95 100

- the back wall of the recess. Extending through the back wall of the recess in each box is a small opening *l*, disclosing a portion of the journal and its bearing, and especially the contact of the journal with the bearing, so that the lubricant after being used will be discharged through the opening *l*. While serving this purpose the opening is also designed for facilitating the removal of the bearing when it becomes worn, which is accomplished with great ease by removing the bearing-box from the brackets, if necessary, and driving out the bearing by inserting a punch through the opening *l*.
- 15 Each bracket *F* is provided with the two upright supports *H*, each of which is provided with the curved recess or slot *m* to form the bearings for the trunnions *a a*. Each bearing-box being supported only upon the trunnions to allow the box a free movement in the direction of the shaft's length, they will accommodate themselves to the journals and give a uniform bearing-surface by the uniformity of contact which becomes necessary
- 20 to better keep the oil on the bearings and prevent friction on any one part more than on another, which would result in wearing the bearing-surfaces irregularly.

What I claim is--

1. A device for supporting a cable-carrier shaft, consisting of the bearing-boxes provided with oil-cups and having trunnions formed thereon, in combination with suitable brackets on which said trunnions bear, said brackets being provided with recesses or slots adapted to receive the trunnions, substantially as described, whereby the trunnions will permit the bearings to accommodate themselves to the shaft, as and for the purpose set forth.

2. A device for supporting a cable-carrier shaft, consisting of the bearing-boxes provided with oil-cups and with trunnions, in combination with brackets on which said trunnions rest, the said bearing-boxes being each provided with recesses adapted to receive a lignum-vitæ bearing and the end of the shaft, and having an opening through its back wall, substantially as described, and for the purpose set forth.

In testimony whereof I affix my signature in the presence of two subscribing witnesses.

GEORGE ST. PIERRE.
